Fig. 1.

Fig. 2.

Fig. 3.

A diagram of a container with a ribbed base and a textured top. The container is shown from a slightly elevated angle, revealing its rounded base with a ribbed pattern. The top surface is textured with a grid-like pattern. The container appears to be made of a flexible material, possibly a pouch or a small bag.

UNITED STATES PATENT OFFICE.

EDWARD R. PETRIE, OF NEW YORK, N. Y.

WHISTLE.

Application filed October 6, 1927. Serial No. 224,344.

This invention relates to whistles and particularly to devices of this class adapted to be worn on the finger of a hand; and the object of the invention is to provide a whistle device of the class specified composed of two sheet metal parts adapted when coupled together to form the whistle, and said parts being provided with means for interlocking the same one with the other and to provide a substantially air-tight connection between said parts; a further object being to provide a whistle, the separate parts of which are so coupled together as to permit of the uncoupling of said parts at will for the purpose of cleaning, whereby the whistle may be maintained in perfect, operative condition at all times; a further object being to provide one of the parts of the whistle with extending, curved spring members forming in conjunction with the whistle body, a finger ring or loop for mounting the whistle upon the finger of a wearer, the spring members forming said loop adapting the whistle to fingers of different sizes; and with these and other objects in view, the invention consists in a device of the class and for the purpose specified, which is simple in construction, efficient in use, and which is constructed as hereinafter described and claimed.

The invention is fully disclosed in the following specification, of which the accompanying drawing forms a part, in which the separate parts of my improvement are designated by suitable reference characters in each of the views, and in which:

Fig. 1 is a longitudinal, sectional view through a whistle made according to my invention.

Fig. 2 is a perspective view of one of the parts of the whistle device shown in Fig. 1.

Fig. 3 is a perspective view of the other whistle part.

Fig. 4 is a section on the line 4—4 of Fig. 1; and,

Fig. 5 is a view similar to Fig. 1 but showing a slight modification.

In the construction shown in Figs. 1 to 4 inclusive, I employ two whistle parts or bodies 10 and 11, the part 10 constituting the casing portion of the whistle and comprising a top wall 12, side walls 13 and an end wall 14, forming at one end of the part 10, a box-shaped or cup-shaped portion. The top wall at the other end of the part 10 extends in a lip portion 15 which curves onto the sides 13, the latter being cut away as shown

at 13^a. The top wall is also provided with an aperture 16 which extends to a slight degree onto both of the side walls 13, the aperture having a straight front wall 16^a and an arc-shaped or curved rear wall 16^b.

In the construction shown, the side walls 13 are provided substantially centrally thereof with depending curved spring members 17 which form, in conjunction with the body 15 of the whistle, a finger ring or loop, in which a finger of the hand is adapted to be placed in mounting the whistle on the hand. The inner faces of the side walls 13, and the end wall 14 are provided with grooves 18, note Figs. 1 and 4, which provide for the locking of the parts 11 in connection with the part 10, as later described.

The part 11 is also fashioned from sheet metal and comprises a bottom wall 19, side walls 20 and an end wall 21 forming a substantially box-shaped end portion which is adapted to fit within the box-shaped portion of the part 10 in the manner shown in Figs. 1 and 4 of the drawing. The bottom wall 19 is extended at the open end of the box member and is curved upwardly and outwardly in the form of a lip portion 22 which is in alignment with the curvature and inclination of the side walls 13 as set out at 13^a. This lip portion is bent backwardly upon itself as seen at 23 at the outer end of the lip portion 15 and extends upwardly to form a guide panel 24 which terminates in a shoulder or ledge 25 adjacent the aperture 16, the strip continuing into the box-shaped end portion in a downwardly, backwardly and upwardly curved supplemental bottom member 26 which fits within the side walls 20, and the end wall 21 forming between it and the top and side walls of the part 10, a sound chamber 27 in which may be placed a ball or other movable member 28.

It will be noted that the member 24 in its upward inclination forms a contracted passage 29 adjacent the aperture 16 whereby the blast of air passed into the chamber 30 leading to said passage will be directed onto the curved wall 16^b of the aperture 16 to produce the proper whistle tone, part of the air entering the chamber 27 and agitating the ball 28 therein if such ball be employed. It will be understood that the height or inclination of the member 24 may be varied to suit the desired or required whistle tone or pitch.

The side walls 20 and the end wall 21 are provided with outwardly projecting beads 31,

which are adapted to operate in the grooves 18 on the inner faces of the side walls 13 and end wall 14 of the part 10 in coupling said parts together, and to provide a substantially 5 air-tight connection between said parts to prevent the escapement of air passed into the chamber 27 except outwardly through the discharge aperture 16, whereby the full blast of air may be utilized in producing the whistle 10 sound or tone.

In Fig. 5 of the drawing, I have shown a slight modification wherein the extension of the bottom wall 19 from the member 24, instead of being in the form of a single arc-shaped member as the member 26, is fashioned into two arc-shaped members 32 and 33 forming within and between the whistle parts, separate sound chambers 34 and 35 in which balls 36 and 37 may be placed, the chamber 20 34 registering with the aperture 16, whereas the chamber 35 registers with another aperture 38 similar to the aperture 16 but arranged rearwardly thereof. Intermediate the chambers 34 and 35 is formed a supplemental 25 traction chamber 39 by an upwardly inclined lip portion 40 to direct the air blown into the chamber 34 to the aperture 38 and the chamber 35.

Aside from the structure above described, 30 the whistle tone in Fig. 5 will be the same as the whistle shown in Figs. 1 to 4 inclusive except that if it be desired, the body of the whistle shown in Fig. 5 may be longer. This type of a whistle, will produce a dual 35 or two-tone sound as compared with the single tone or pitch sound of the whistle shown in Figs. 1 to 4 inclusive.

In both forms of construction shown, the 40 separate parts 10 and 11 of the whistle, may be stamped or pressed from sheet metal into the desired form, and said parts coupled and uncoupled whenever desired by virtue of the 45 interlocking means employed. In this way, the chamber or chambers within the whistle may be kept clean, and the inner surfaces 50 of the whistle cleaned at all times, to maintain the whistle in a properly functioning as well as sanitary condition at all times. It will be understood that the part 11 is slid into the part 10 by placing the beads or 55 projections 31 in the grooves 18 at the mouth-piece end of the whistle and sliding the parts one upon the other until the bead of the end wall 21 enters the groove 18 in the end wall 14. In dissecting the parts, the nail of a 60 finger may be placed between the end walls 21 and 14 or a knife or similar tool used for this purpose.

In all types of whistle devices, it is com- 60 monly experienced that the sound chamber thereof as well as the air admission chamber in the mouth piece becomes clogged with dust, dirt and foreign matter, especially in carrying the same about in a pocket when the same 65 is not in use, or in the use of the device, the

collection of moisture from the mouth, in the device, renders the same not only inoperative but unsanitary, in that the ability to thoroughly clean the whistle is rendered impossible by virtue of the unit structure 70 thereof. With my improved whistle device, however, these objectionable features are obviated, and the whistle may be kept in a clean, 75 sanitary and operative condition at all times.

It will be understood that while I have 80 shown a whistle of specific form and construction, that my invention is not necessarily limited to the whistle herein shown and described, and various changes therein and modifications thereof may be made within 85 the scope of the appended claims, without departing from the spirit of my invention, or sacrificing its advantages.

Having fully described my invention, what 90 I claim as new and desire to secure by Letters Patent, is:—

1. A whistle device comprising two independently formed box-shaped parts adapted to be placed one within the other and forming a chamber therebetween, each of said parts having at one end, projecting lip portions forming the mouth piece end of the whistle device, said device having a discharge opening communicating with said chamber, and means for coupling said parts together to prevent accidental displacement and permitting of the separation of said parts at will for cleaning and other purposes.

2. A whistle device comprising two independently formed box-shaped parts adapted to be placed one within the other and forming a chamber therebetween, each of said parts having at one end, projecting lip portions forming the mouth piece end of the whistle device, said device having a discharge 100 opening communicating with said chamber, and means for coupling said parts together to prevent accidental displacement and permitting of the separation of said parts at will for cleaning and other purposes, said 105 coupling means being of tongue and groove construction to provide a seal between the separate parts to prevent the escapement of air therebetween, in the operation of the whistle.

3. A whistle device comprising two independently formed box-shaped parts adapted to be placed one within the other and forming a chamber therebetween, each of said parts having at one end, projecting lip portions forming the mouth piece end of the whistle device, said device having a discharge 110 opening communicating with said chamber, means for coupling said parts together to prevent accidental displacement and permitting of the separation of said parts at will for cleaning and other purposes, said 115 coupling means effecting a seal between the separate parts to prevent the escapement of air therebetween in the operation of the whistle 120

and an arc-shaped portion on one of said parts extending into the sound chamber formed therebetween.

4. A whistle device comprising two independently formed box-shaped parts adapted to be placed one within the other and forming a chamber therebetween, each of said parts having at one end, projecting lip portions forming the mouth piece end of the whistle device, said device having a discharge opening communicating with said chamber, means for coupling said parts together to prevent accidental displacement and permitting of the separation of said parts at will for cleaning and other purposes, said coupling means effecting a seal between the separate parts to prevent the escapement of air therebetween in the operation of the whistle, an arc-shaped portion on one of said parts extending into the sound chamber formed therebetween, and the lip portion of one of said parts having an upwardly inclined surface forming a contracted passage opening into said sound chamber.

5. A whistle device comprising two independently formed box-shaped parts adapted to be placed within the other, each of said parts having at one end, projecting lip portions forming the mouth piece end of the whistle device, means for coupling said parts together to prevent accidental displacement and permitting of the separation of said parts at will for cleaning and other purposes, said coupling means effecting a seal between the separate parts to prevent the escapement of air therebetween in the operation of the whistle, an arc-shaped portion on one of said parts extending into the sound chamber formed therebetween, the lip portion of one of said parts having an upwardly inclined surface forming a contracted passage opening into said sound chamber, one of said parts having a discharge aperture arranged adjacent said contracted passage, and one of said parts having projecting and oppositely disposed spring members, forming between the same and the body of the whistle, a finger ring or loop.

6. A whistle device comprising two independently formed box-shaped parts adapted to be placed one within the other, each of said parts having at one end, projecting lip portions forming the mouth piece end of the whistle device, means for coupling said parts together to prevent accidental displacement and permitting of the separation of said parts at will for cleaning and other purposes, said coupling means effecting a seal between the separate parts to prevent the escapement of air therebetween in the operation of the whistle, two arc-shaped portions on one of said parts and extending into the chamber between said parts to form two sound chambers therein, and one of said parts having two discharge apertures adapted to register with

the separate sound chambers of the whistle body.

7. A whistle device comprising two independently formed box-shaped parts adapted to be placed one within the other, each of said parts having at one end, projecting lip portions forming the mouth piece end of the whistle device, means for coupling said parts together to prevent accidental displacement and permitting of the separation of said parts at will for cleaning and other purposes, said coupling means effecting a seal between the separate parts to prevent the escapement of air therebetween in the operation of the whistle, two arc-shaped portions on one of said parts and extending into the chamber between said parts to form two sound chambers therein, one of said parts having two discharge apertures adapted to register with the separate sound chambers of the whistle body, and means on one of said parts adjacent each of said apertures for forming contracted passages leading to said sound chambers.

8. A whistle device comprising two independently formed box-shaped parts adapted to be placed one within the other, each of said parts having at one end, projecting lip portions forming the mouth piece end of the whistle device, means for coupling said parts together to prevent accidental displacement and permitting of the separation of said parts at will for cleaning and other purposes, said coupling means effecting a seal between the separate parts to prevent the escapement of air therebetween in the operation of the whistle, two arc-shaped portions on one of said parts and extending into the chamber between said parts to form two sound chambers therein, one of said parts having two discharge apertures adapted to register with the separate sound chambers of the whistle body, means on one of said parts adjacent each of said apertures for forming contracted passages leading to said sound chambers, and two arc-shaped spring members on one of said parts and forming a finger ring or loop.

9. A whistle device composed of two independently formed sheet metal and substantially box-shaped parts forming a sound chamber within and between said parts when coupled together, means for admitting air to said chamber, and a discharge aperture through which air blown into said chamber is free to pass, and means for detachably coupling said parts whereby said parts may be separated for cleaning or other purposes.

10. A whistle device composed of two independently formed sheet metal and substantially box-shaped parts forming a sound chamber within and between said parts when coupled together, means for admitting air to said chamber and a discharge aperture through which air blown into said chamber is free to pass, and means for detachably coupling said parts whereby said parts may

be separated for cleaning or other purposes, said last named means involving tongue and groove portions serving to seal the connection between said parts to prevent the escapement 5 of air therebetween.

11. A whistle device composed of two independently formed sheet metal and substantially box-shaped parts forming a sound chamber within and between said parts when 10 coupled together, means for admitting air to said chamber and a discharge aperture through which air blown into said chamber is free to pass, means for detachably coupling said parts whereby said parts may be separated 15 for cleaning or other purposes, said last named means also serving to seal the connection between said parts to prevent the escapement of air therebetween, and means on one of said parts extending from the body 20 of the whistle for mounting the same in connection with a suitable support.

12. A whistle device composed of two independently formed sheet metal and substantially box-shaped parts forming a sound chamber within and between said parts when 25 coupled together, means for admitting air to said chamber and a discharge aperture through which air blown into said chamber is free to pass, means for detachably coupling

said parts whereby said parts may be separated for cleaning or other purposes, said last named means also serving to seal the connection between said parts to prevent the escapement of air therebetween, and means on one of said parts extending from the body 30 of the whistle for mounting the same in connection with a suitable support, said means comprising oppositely disposed arc-shaped 35 spring members.

13. A whistle device fashioned from two sheet metal parts, each of said parts having a mouthpiece portion, forming when said bodies are coupled together the mouthpiece end portion of the device, one of said parts being substantially box-shaped in form and 40 forming between it and the other part, a chamber, said device having an aperture opening into said chamber adjacent the mouthpiece end portion thereof, and one part of the device have oppositely disposed arc-shaped members extending from the body of 45 the whistle, in common alinement and forming in conjunction with the whistle, a split, finger engaging ring.

In testimony that I claim the foregoing as 50 my invention I have signed my name this 3rd day of October, 1927.

EDWARD R. PETRIE.
